Fig. 5.

Fig. 6.

Fig. 7.

Fig. 8.

FIG. 1 is a front top perspective view of a speaker telephone showing my new design;

FIG. 2 is a rear top perspective view thereof;

FIG. 3 is a top plan view of the speaker telephone as shown in FIGS. 1 and 2;

FIG. 4 is a rear end view of the speaker telephone shown in FIG. 3;

FIG. 5 is a side view of a speaker telephone shown in FIG. 3;

FIG. 6 is a front top perspective view of a speaker in FIG. 3;

FIG. 7 is a bottom plan view of the speaker telephone shown in FIG. 7 and

FIG. 8 is a side view of the speaker telephone shown in FIG. 7.

I claim:

The ornamental design for a speaker telephone, substantially as shown in the drawings and photographs.
